ELECTRICAL OUTLET

Walter J. Duffy, North Bergen, N. J.

Application December 10, 1936, Serial No. 115,231

1 Claim. (Cl. 38—142)

This invention appertains to new and useful improvements in outlets for electricity and more particularly to a small compact cabinet for electrical sadirons.

5 The principal object of the present invention is to provide an iron cabinet wherein an electrical socket is provided which can be used for supplying energy to any appliance including or aside from the iron housed by the cabinet.

10 Another important object of the invention is to provide an iron cabinet in which a conductor reel is provided on which the conductor cord of the iron can be wound.

15 These and various other important objects and advantages of the invention will become apparent to the reader of the following specification.

In the drawings:—

Figure 1 represents a front elevational view of the cabinet with the closure in closed position.

20 Figure 2 represents a front elevational view of the cabinet with the closure in open position.

Figure 3 is a vertical sectional view on the line 9—3 of Figure 1.

25 Figure 4 is a fragmentary horizontal sectional view on the line 4—4 of Figure 2.

Figure 5 is an inside elevational view of the selector rings of the electrical connector.

30 Figure 6 is a side elevational view of the spool end with the contact brushes thereon for engagement with the rings shown in Figure 5.

Figure 7 represents a front elevational view of a modified form of cabinet in which the socket is on the outside of the door.

35 Figure 8 is a front elevational view of the cabinet shown in Figure 7 showing the connector supported on the internal partition of the cabinet.

Referring to the drawings wherein like numerals refer to like parts, it can be seen that numeral 40 5 generally refers to the cabinet which consists of the back wall 6, top wall 7, bottom wall 8 and side walls 9—9.

Supported within the cabinet 5 is the supplemental back wall 10 spaced from the back wall 6 and this back wall 10 is provided with a forwardly extending upper wall portion 11 spaced from the top wall 7 and having a downwardly curved forward end portion 12. The lower portion of the supplemental wall 10 is disposed forwardly as at 13 and then downwardly to form the vertical partition 14 at the lower portion of the cabinet and to define the reel compartment 15 in which are located the uprights 16—17 in which the ends of the shaft 18 are disposed, the 55 end of the shaft disposed to the upright 16 being

squared as at 19. The spool 20 having the end circumferential flanges 21—22 is rotatable on the shaft 18 and a coiled compressible spring 23 is convoluted on the shaft 18 and has one end engaged with the spool 20 and the other end with the shaft. Numeral 24 represents the iron cord which is wound on the spool 20 by the spring 23 and extends through the opening 25 in the partition 14 to connect to the iron plug 26, which plug is supported on the outside of the partition 14 by spring clips 27.

As shown in Figure 4 the upright 17 has the plate 28 of insulation secured thereto and on the side of the plate 28 opposed to the spool flange 21 are the conductor rings 29—30 through 15 which the conductors of the cord 24 of the electrical supply cable are connected.

As is shown in Figure 6, the spool flange 21 is provided with the contact brushes 31—32 thereon for engagement with the rings 29—30, respectively, and to the brushes 31—32 are connected the ends of the cord 24.

The portion 13 of the supplemental back wall 10 (see Figure 3) is provided with a V-shaped trough 33 for receiving the usual V-shaped rest 34 of the electric iron 35, while a pair of spring detents 36—36 on the upper portion of the partition 10 serve to hold the nose portion of the iron. The iron is of conventional design and has the usual socket 37 for receiving the connector plug 30

25 The vertical edge portions of the outer parts of the side walls 9—9 as well as the bottom wall 8 are provided with a guide trough 38 for the flexible closure 39 which can be slid upwardly 35 and rearwardly between the back wall 6 and supplemental wall 10, that is, in the space 40.

A modified form of the invention is shown in Figures 7 and 8 wherein the cabinet 41 is provided with a hinged closure 42 on which the electric socket 43 is located. It will be observed in Figure 2 that the electrical socket is located within the cabinet and on the partition 14 and at this point it is denoted by reference character 44.

45 However, in the form of the invention shown in Figures 7 and 8 the socket 43 is located on the outside of the door 42 as it is only necessary to open the door 42 when the connector plug 44 is desired for use in connection with an electric 50 iron or some other electrical appliance, where it will be supported by the spring clips 45—45 on the internal partition 46 of the cabinet 41. The cord 48 thereof extending through the opening 47 in the partition 46 to a reel in the cabinet and 55

behind the partition, not shown in the drawings. While the foregoing specification sets forth the invention in specific terms, it is to be understood that numerous changes in the shape, size and materials may be resorted to without departing from the spirit and scope of the invention as claimed hereinafter.

What is claimed is:—

A cabinet structure comprising a box-like structure having an open front and including back and top walls, a false back wall in the box-like structure in spaced relation to the back wall and having a forwardly extending portion in spaced relation to the top wall, said false back wall and

extension defining in cooperation with the back and top walls of the box-like structure, a guideway, a flexible closure slidably disposed across the front of the box-like structure and into the said guideway, the lower portion of the said false back wall being disposed forwardly in the box-like structure and then downwardly to meet the bottom of the box-like structure and to define a compartment, a conductor reel in the compartment, and means on the last-mentioned portion 10 of the false back wall adapted to support an electrical connector having its conductor disposed on the said reel.

WALTER J. DUFFY.
